UNITED STATES PATENT OFFICE.

GEORGE A. JESSOP, OF YORK, PENNSYLVANIA, ASSIGNOR TO S. MORGAN SMITH COMPANY, OF YORK, PENNSYLVANIA, A CORPORATION.

PLATE-STEEL WICKET GATE FOR TURBINES.

Application filed September 25, 1926. Serial No. 137,796.

This invention relates to a plate steel wicket gate for use in connection with hydraulic turbines or water wheels.

As readily understood, these gates are 5 opened and closed to control the quantity of water flowing to a turbine runner to regulate the H. P. output. These gates have usually been cast in one piece of metal, either cast-iron, steel or bronze, and the 10 advantage of the plate steel gate is that casting strains are eliminated, especially in the vicinity of the operating stem, and equal strength can be obtained by the use of lighter material, and as a consequence a 15 gate lighter in weight and of less expense can be manufactured. By torsional and other tests, it has been found that these plate steel gates are of ample strength to perform the work required with the usual 20 factors of safety.

The primary object of the present plate steel gate is to generally improve this class 25 of gates by applying the stems thereto in a strong and durable manner by utilizing reinforcing or bracing means therefor extending through the guide surfaces and secured 30 positively and flush in the plates forming the said surfaces, instead of abutting the reinforcing or bracing means against the plates, with material advantage in the formation of the gate.

A further object of the invention is to provide a gate of the class specified with conduit or tubular means in the stems to 35 facilitate a thorough and practical lubrication of the bearings for the gates, and thereby adding to the durability of the gates.

With the foregoing objects and other 40 structural advantages which will herein-after appear, the invention consists in the preferred construction and arrangement of parts described in the subjoined specification and pointed out in the claims.

45 In the drawings:

Figure 1 is a top plan view of a part of the improved gate showing the improved features thereof in dotted lines;

Fig. 1^a is a similar view of the remaining 50 portion of the improved gate;

Fig. 2 is a side elevation of a portion of the gate, showing the improvements in full and dotted lines;

Fig. 3 is an enlarged, partial transverse

vertical section of the gate broken away in 55 parts;

Fig. 4 is a top plan view of the gate in modified form;

Fig. 5 is an enlarged transverse section on the line 5—5, of Figure 4; and 60

Fig. 6 is a detail side elevation, partially broken away, of a portion of the structure, showing a slight modification.

Referring to Figs. 1 to 3, inclusive, the 65 guide surfaces of the gates are formed of two sheets 5 and 6, which are cut out of flat, standard sheet steel and then pressed to the proper shape on dies in a hydraulic press. The upper and lower pivots or stems 7 and 8 are pieces of standard size of round bar 70 iron, which are unfinished where covered by the guiding plates constituting the guide surfaces and finished true to size where they extend out of the gate at the top and bottom. To each of the stems 7 or 8 are welded ribs 75 or plates 9 and 10 which are in general of somewhat heavier material than the guiding plates 5 and 6. The ribs 10 are preferably narrower than the ribs 9, but both ribs 9 and 10 extend laterally entirely to the outside 80 or guide surfaces of the guiding sheets 5 and 6, and furthermore, the outer extremities of the said ribs are welded to the guiding sheets with their ends coincident with the outer guiding surfaces of the sheets. The guiding 85 sheets 5 and 6 are notched out as at 9^a and 10^a by shearing or by means of a welding or burning torch or other means applied where the notches are to be formed for receiving the ends of the ribs. The notches 9^a and 10^a 90 are somewhat larger than the ribs which are to be inserted therein, thus allowing ample provision for welding by suitable material as at 9^b and 10^b, see Fig. 3, and also the notches do not have to be made to exact dimensions but can be shaped approximately, the spaces around the ends of the ribs being 95 filled with welding material. The notches 9^a and 10^a are precisely similar and are cut as above explained through the guide sheets 100 in dimensions proportionate to the dimensions of the ribs 9 and 10 but of greater dimensions than the latter, as above explained. Both ribs have their ends extending entirely through the guiding sheets 5 and 6 and are similarly attached to the latter.

In constructing the improved gate, the

process is first to weld the ribs 9 and 10 to the stems, then cut the sheets 5 and 6 from flat material and form the proper notches or slots in these sheets to receive the ends of the ribs, then bring the sheets to proper formation on a hydraulic press with correctly shaped dies, then place these two guiding sheets over the stems with their ribs and weld the guiding sheets at 5^a and 6^a, see Fig. 1, and finally weld the ribs 9 and 10 to the guiding sheets 5 and 6. The upper stems 7 are much longer than the lower stems for giving ample bearing to the former and also attaching the operating parts which are usually found in connection with wicket gates and included in the turbine organization.

One of the advantages of this gate is that the operating stem 7, which is also a supporting stem, does not necessarily extend entirely through the gate but is separated from the stem 8 which is a supporting stem only. There will be a bearing at the lower part of the gate for the stem 8, and in general two bearings in addition to an operating arm 25 and a packing box on and operating with the supporting and operating stem 7. The stem 7 in general is drilled to form a hole 11 for grease lubrication, that is, grease is forced down through the hole 11 bored through the stem with an outlet at each bearing. To the lower end of the stem 7 below the rib 10 a pipe 13 is secured and extends entirely through the lower stem 8, which is also drilled through its entire length, as at 30 12, rendering it tubular for the reception of the pipe 13. The pipe 13 terminates at the lower end of the stem 8 and is plugged shut at the end and the grease is forced through this pipe to a small outlet leading to the bearing in which the supporting stem 8 is mounted and in which it has movement.

Referring to Figs. 4 and 5, a somewhat different type of gate construction is illustrated. The gate in this particular instance is somewhat smaller in size, and therein the outer guiding means consists of outer plates 14 and 15 which are shaped as before explained and welded as at 14^a and 15^a. In this modified form of gate the pivot means comprises bosses 16 and 17 which are welded by means of end contact to the plates 14 and 15, the said bosses being extended laterally as at 18 through suitably sized openings in the opposite plates 14 and 15, through which the lateral extensions of the bosses are inserted and terminating flush with the outer guiding sides of the plates 14 and 15 and secured in place by welding with suitable material. These bosses are bronze-bushed as 45 at 19 and 20, and these bronze bushings form the bearings for the gate stem or pin inserted therethrough, the gate stems or pins being omitted in this instance. For operating this gate a boss 21 is welded at one end of the gate as shown by Fig. 5 and to the same suit-

able operating means will be connected. This boss is applied by welding means as at 22, Figs. 4 and 5; and the same characteristics of the supports extending through the side plates 14 and 15 is carried out in connection with these latter parts as with the bosses 16 and 17. The welding is done in all instances by means of end contact of the guiding sheets where they are welded to the bosses.

The grease lubrication feature is slightly modified in Fig. 6, and in this modification a pipe 13^a is connected to the lower end of the stem 7 and to the upper end of the stem 8, the said pipe 13^a passing only into the lower stem 8 far enough to secure the pipe but not entirely through the said stem as in the previous structure. By this means the hole through the stem 8 can be smaller or of the same size as the hole in the stem 7. The remaining structure of this modification is precisely the same as that heretofore described, and similar reference numerals are applied thereto to indicate corresponding parts.

It will be seen from the foregoing that both forms of the gate embody the essential feature of having the supports for the pins in the form of ribs or bosses, as explained, laterally extended through the guiding plates 5 and 6 or 14 and 15 of the respective figures, and hence the construction is reinforced and solidified or strengthened in the same manner.

Considerable material and labor is saved, especially in the first form of the device, by extending the stems only partially through the gate. The shape of the gate is such that there is a great natural and inherent strength and stiffness and it is unnecessary to have the stems go entirely through the gate. These shorter stems also save a great deal of expense because the hole through the center of the gate must be drilled and the difficulty of drilling these small diameter holes increases more rapidly than in direct proportion to the length or depth of the drilling. Furthermore, for large gates where the saving by the use of sheet steel and the advantages of strength are more apparent in this improved construction of gates, it is unnecessary to have the stem of sufficient size to come into direct contact with the guiding surfaces of the gate, and therefore the stems can be selected of the size required for proper strength as compared to structures heretofore employed and wherein the stem extends entirely through or to the guiding plates and must be of the size determined by the thickness of the gate at this point rather than as required for strength. For large gates, this will mean a great saving in material, and particularly where the head under which the gate is operating is low or medium.

What I claim as new is:—

1. A plate steel wicket gate comprising opposite properly shaped guiding members, pivot means spaced between said members, and means extending outwardly from the pivot means and through the said guiding members and terminating coincident with the outer surfaces of the latter for holding the pivot means in place. 5
- 10 2. A plate steel wicket gate comprising opposite properly shaped guiding members, pivot means arranged between the inner sides of said members, and elements connected to the pivot means and extending through 15 and secured to the said members for holding the pivot means in place, the said means terminating coincidentally with the outer sides of the members and welded to the latter. 15
- 20 3. A plate steel wicket gate comprising opposite continuous plate steel guiding members, stems between said members, and means extending laterally through the members for holding the stems in place between the members, the said means extending 25 through openings formed in the members and terminating coincidentally with the outer surfaces of the members and welded to the latter. 30
- 35 4. A plate steel wicket gate comprising opposite properly shaped plate steel guiding members, stems spaced between the inner surfaces of said members and means connected to the stems and extending laterally through different portions of the members for holding the stems in place between the said members, the said means extending through the members and terminating coincidentally with the outer surfaces of the members and welded to the latter. 40
- 45 5. A plate steel wicket gate comprising opposite properly shaped plate steel guiding members, stems arranged between the walls of said members for holding the stems in place between the members, the said means terminating coincidentally with the outer surfaces of the guiding members. 50
- 55 6. A plate steel wicket gate comprising opposite properly shaped plate steel guiding members and stems, the stems extending partially through the gate, and means extending laterally through the members and terminating coincidentally with the outer surfaces of the said members for holding the stems in place, the means varying in width. 55
7. A plate steel wicket gate comprising opposite properly shaped plate steel guiding members, stems extending partially through the members and ribs varying in width extending laterally through the members for holding the stems in place between the members, the said ribs being wider at the ends of the gates than interiorly thereof and extending through openings formed in the members and terminating coincidentally with the outer surfaces of the members and secured to the latter. 60
- 10 8. A plate steel wicket gate comprising opposite properly shaped plate steel guiding members, stems extending partially through the said members, the said stems being longitudinally bored for receiving lubricant, the inner terminal of the one stem having a pipe extending through the bore of the opposite stem to convey the lubricant from one stem to the other and also serve as additional reinforcing means, and ribs extending laterally through the members for holding the stems in place between the members, the ribs terminating coincidentally with the outer surfaces of the members and welded to the latter. 75
- 15 9. A plate steel wicket gate comprising opposite properly shaped plate steel guiding members, and stems of different length disposed in the ends of the members and extending partially through the latter, the stems being tubular and interiorly connected by a pipe to permit lubricating grease to be forced through one stem into and through the other. 85
- 20 10. A plate steel wicket gate comprising opposite properly shaped plate steel guiding members, and stems of different length disposed in the ends of the members and extending partially through the latter, the stems being tubular and the one stem having a pipe connected to the inner end and extending through the opposite stem. 95
- 25 11. A plate steel wicket gate comprising opposite properly shaped plate steel guiding members, and stems of different length disposed in the ends of the members and extending partially through the latter, the stems being tubular and the one stem having a pipe connected to the inner end and extending through the opposite stem, the stems having brace means extending through and terminating with the outer surfaces of the members and secured to the latter. 100

In testimony whereof I have hereunto set my hand.

GEORGE A. JESSOP.
